UNITED STATES PATENT OFFICE.

ROBERT A. LUNDELL, OF NEW YORK, N. Y., ASSIGNOR TO INGERSOLL-RAND COMPANY, OF JERSEY CITY, NEW JERSEY, A CORPORATION OF NEW JERSEY.

PISTON AND CONNECTING-ROD CONSTRUCTION.

1,423,344.

Specification of Letters Patent.

Patented July 18, 1922.

Original application filed April 18, 1918, Serial No. 229,306. Patent No. 1,371,701, dated March 15, 1921.
Divided and this application filed February 18, 1921. Serial No. 446,058.

To all whom it may concern:

Be it known that I, ROBERT A. LUNDELL, a citizen of the United States, and a resident of the borough of Manhattan, city, county, 5 and State of New York, have invented a certain Piston and Connecting-Rod Construction, of which the following is a specification accompanied by drawings.

This invention relates to engines, but more 10 particularly to multiple cylinder V-type engines adapted to be operated by fluid under pressure, as for instance compressed air, for high speed rotating tools or machines, the present application being a division of my 15 copending application Serial No. 229,306 filed April 18, 1918.

In an engine of this type, the cylinders are ordinarily located at equal acute angles on opposite sides of a plane passing through 20 the axis of the crank shaft, and the axes of the cylinders form an angle of approximately 90 degrees in practice, although this angle may be more or less than that, and between about 30 degrees and about 120 25 degrees as desired.

The usual method of assembling the pistons in the cylinders is to first insert the pistons and connecting rods into the cylinders, before assembling the connecting rods 30 on the crank pin or pins of the crank shaft, necessitating some form of split or open connecting rod end which in the limited space of small engines can not be made as substantial and durable as a closed end one 35 piece connecting rod, as shown in the present instance. Particularly in small engines, difficulties are experienced in so assembling the parts, owing to the confined space in which to adjust the bearings and other 40 parts, after the pistons and connecting rods are in position in the cylinders.

The primary object of the present invention is to obviate these and other disadvantages of such methods of assembly known 45 to those skilled in the art, by forming the crank shaft, connecting rods and pistons as a single unit with provision for permitting the pistons to be inserted in the cylinders after the connecting rods have first been 50 assembled in the pistons and on the same crank pin. By this means all the adjustments on the pistons and crank pin are conveniently made on the bench before the pistons are placed in the cylinders, and further-

more the connecting rods may be provided 55 with continuous bearing rings adapted to be slipped over the crank endwise instead of the usual split bearing sleeves or rings which are required in the usual methods.

The invention is illustrated in the accompanying drawing in which the figure is a longitudinal sectional view through two cylinders of a V-type engine, but transverse to the axis of the crank shaft.

Referring to the drawing, the cylinders 65 18 are arranged in the cylinder body with their axes at an angle of about 90 degrees or a little greater in the present instance, and said cylinders as shown are located at equal acute angles on opposite sides of a 70 plane passing through the axis of the crank, the crank pin 15 being indicated in section.

Suitable pistons 10 are adapted to operate in the cylinders and connecting rods 3 are suitably pivoted to said pistons and in 75 accordance with this invention are adapted to be assembled on the same crank pin 15 before inserting the pistons 10 into the cylinders.

As shown in this instance, the connecting 80 rods 3 are provided with balls 13 at one end pivotally held within the one piece sockets 14 formed in the rearwardly extending integral portions 12 of the piston heads, the edges of the sockets being crimped or 85 formed over to hold the balls, which permits the connecting rods to rock relatively to the pistons. The crank ends of the connecting rods 3 are preferably formed with continuous rings 8 adapted to be slipped 90 over the bearing sleeves 16 in assembling the unitary structure comprising the pistons, connecting rods and crank.

The clearances are such that both pistons 10 may be started into the cylinders 18 at 95 substantially the same time or simultaneously inserted. Provision for such assembly is afforded by cutting away portions of the rims of the pistons, preferably on a bevel, as shown at the points 11 so that 100 when these two bevels are placed together, the angle between the connecting rods 3 is less than the angle between the axes of the cylinders 18 and the pistons may be simultaneously inserted in the cylinders.

In the figure the pistons are shown in the positions they assume as they are being assembled in the cylinders, from which it

will be apparent that the connecting rods 3 have been adjusted at an angle less than the angle between the axes of the cylinders. Such adjustment is permitted because of the 5 cut-away portions 11 of the pistons and by this means the pistons 10 may be simultaneously inserted in the cylinders after the connecting rods have been assembled in the pistons and on the same crank pin 15.

10 I am not to be understood as limiting the invention to the exact form and construction shown as equivalent constructions may be devised within the scope of my claims.

I claim:

15 1. A piston and connecting rod construction for engines comprising a piston, a connecting rod pivotally connected to said piston, a portion of the rim of the piston being cut away at one side, to permit a relatively smaller angular adjustment between two piston rods, to afford provision for assembling a plurality of pistons as a unit in an engine after the connecting rods have been connected to the same crank pin.

25 2. A piston and connecting rod construction for engines comprising a piston, a connecting rod pivotally connected to said piston, a portion of the rim of the piston being cut away on a bevel at one side, to permit a relatively smaller angular adjustment between two piston rods, to afford provision for assembling a plurality of pistons as a unit in an engine after the connecting rods have been connected to the same crank pin.

35 3. A piston and connecting rod construction for engines comprising a hollow piston having an interior socket formed in a rearwardly extending portion of the piston head, and a connecting rod having a ball at one 40 end pivotally held within said socket, a portion of the rim of the piston being cut away at one side to permit a relatively smaller angular adjustment between two piston rods, to afford provision for assembling a plurality of pistons as a unit in an engine after the connecting rods have been connected to the same crank pin.

4. A piston and connecting rod construction for engines comprising a hollow piston having an interior socket formed in a rearwardly extending portion of the piston head, and a connecting rod having a ball at one 50 end pivotally held within said socket, a portion of the rim of the piston being cut away on a bevel at one side to permit a relatively smaller angular adjustment between two piston rods, to afford provision for assembling a plurality of pistons as a unit in an engine after the connecting rods have been connected to the same crank pin. 55

5. A multiple cylinder V-type fluid pressure motor, having a crank shaft and crank, cylinders located at equal acute angles on opposite sides of a plane passing through the axis of the crank shaft, pistons adapted 60 to operate in the cylinders, connecting rods pivotally connected to said pistons and adapted to be assembled on the same crank pin before inserting the pistons into the cylinders, and means permitting said pistons to 65 be simultaneously inserted in the cylinders longitudinally after the connecting rods have first been assembled in the pistons and on the crank pin.

6. A multiple cylinder V-type fluid pressure motor, having a crank shaft and crank, cylinders located at equal acute angles on opposite sides of a plane passing through the axis of the crank shaft, pistons adapted 70 to operate in the cylinders, connecting rods pivotally connected to said pistons and adapted to be assembled on the same crank pin before inserting the pistons into the cylinders, and means for adjusting the connecting rods at an angle less than the angle between the axes of the cylinders, to permit 75 the pistons to be simultaneously inserted in the cylinders longitudinally after the connecting rods have been assembled on the pistons and on the said crank pin. 80

In testimony whereof I have signed this specification.

ROBERT A. LUNDELL.
